TENNIS RACKET RESTRINGER

William A. Nicolas, Macon, Mo.

Application March 29, 1935, Serial No. 13,772

4 Claims. (Cl. 273—73)

This invention appertains to new and useful improvements in means for restringing tennis rackets and like implements of sport.

The principal object of the present invention is 5 to provide a tennis racket restringer which can be easily applied to a tennis racket and employed in a convenient and free active manner to restring a racket without difficulty and at an appreciable saving in time.

10 Another important object of the invention is to provide a tennis racket restringer which takes care of substantially all of the necessary operation incident to restringing a tennis racket.

These and various other important objects and 15 advantages of the invention will become apparent to the reader of the following specification.

In the drawings:

Figure 1 represents a top plan view of the restringer applied to a racket.

20 Figure 2 represents a longitudinal sectional view taken substantially on line 2—2 of Figure 1.

Figure 3 represents a sectional view taken substantially on line 3—3 of Figure 2.

25 Figure 4 represents a perspective view of one of the shafts.

Figure 5 represents a sectional view taken substantially on line 5—5 of Figure 2.

Figure 6 represents a perspective view of one of the clamp shoes.

30 Referring to the drawings wherein like numerals designate like parts, it can be seen that numeral 5 represents a tennis racket frame to be strung with the handle 6 extending therefrom.

The restringer consists of a pair of elongated bars 6—7, the bar 6 being substantially longer than the bar 7. The opposed faces of the bars 6—7 are provided with elongated rubber strips 8 for engaging the racket frame 5 to prevent marring thereof and to prevent slipping of the restringer thereon.

40 Bolt members 9—9 extend upwardly through the end of the bar 7 and also through the hook shaped plate 10—10.

A shaft 11 is provided for each end of the bar 45 6 and this shaft consists of the cylindrical portion 12 provided with a reduced extension 13 having a pin 14 driven therethrough with the end portions thereof covered by a rubber tube sections 15. Each of these shafts 12 is provided with

50 an eye member 16 laterally disposed and a polygonal extension 17 at its upper end for disposition into the corresponding handle bar 18.

The reduced portion 13 is covered by a rubber tube 19 around which the tennis racket string 55 20 is to be wound in tightening the same.

It will be observed in Figure 2, that each of the bolts 9 extend through an opening 20' in an arcuate shaped shoe 21, the contact side of which is provided with a rubber plate 22. The threaded portion of each of the bolts 9 is provided with a wing nut 23.

A plurality of openings 24 is provided in each end of the bar 6 concentrically arranged with respect to the shaft 11 and a pin member 25 can be disposed through the corresponding eye member 16 and into the corresponding opening 14 to retain the string 20 at whatever tautness is desired.

It will be observed, that in first starting to string the racket, the string is knotted as at 25 15 and then disposed across the frame and tightened by the corresponding shaft 11, after which the bars 6—7 are shifted slightly so that one of the tubes 9 engages over the external portion of the string 20 and by tightening through the use of 20 the corresponding wing nut 23, the shoe 21 in place against the string, the string will be retained in this taut position while it is removed from the adjacent shaft reduced extension 13 and trained back across the frame and subsequently 25 attach the shaft 11 at the opposite end of the bar 6.

This operation is repeated from time to time, bearing in mind to employ the clamp shoe 21 to retain the last section of the string trained 30 while the next section is to be trained.

While the foregoing specification sets forth the invention in specific terms, it is to be understood that numerous changes in the shape, size and materials may be resorted to without departing from 35 the spirit or scope of the invention as claimed hereinafter.

Having described the invention, what is claimed as new is:

1. A tennis racket restringer comprising a pair 40 of bar members, one of said bar members being provided at its ends with rotary shafts, swingable bearing members on the other bar member for engaging the said shafts and being removable therefrom, means on the bars for clamping the 45 same together against a tennis racket, said means including clamp shoes for engaging and holding a tennis racket string while the racket is being strung.

2. A tennis racket restringer comprising a pair 50 of bar members, one of said bar members being provided at its ends with rotary shafts, swingable bearing members on the other bar member for engaging the said shafts and being removable therefrom, means on the bars for clamping the 55

same together against a tennis racket, said means including clamp shoes for engaging and holding a tennis racket string while the racket is being strung, and means for retaining the said 5 shafts in string tightened position.

3. A tennis racket restringer comprising a pair of bar members, one of said bar members being provided at its ends with rotary shafts, swingable bearing members on the other bar member for 10 engaging the said shafts and being removable therefrom, means on the bars for clamping the same together against a tennis racket, said means including clamp shoes for engaging and holding a tennis racket string while the racket is being 15 strung, said shafts being provided with a re-

silient covering around which the racket string is wound.

4. A tennis racket restringer comprising a pair of bar members, one of said bar members being provided at its ends with rotary shafts, swingable bearing members on the other bar member for engaging the said shafts and being removable therefrom, means on the bars for clamping the same together against a tennis racket, said means including clamp shoes for engaging and holding a tennis racket string while the racket is being 10 each of the said shafts being provided with a cross handle at one end thereof.

WILLIAM A. NICOLAS. 15
